DESIGN.

—o—
J. P. HARRIMAN.

ORNAMENTATION OF KNIT FABRICS.

U. S. 18,361.

Patented June 5, 1888

UNITED STATES PATENT OFFICE.

JEREMIAH P. HARRIMAN, OF WOONSOCKET, RHODE ISLAND.

DESIGN FOR THE ORNAMENTATION OF KNIT FABRICS.

SPECIFICATION forming part of Design No. 18,361, dated June 5, 1888.

Application filed March 10, 1888. Serial No. 266,581. Term of patent 14 years.

To all whom it may concern:

Be it known that I, JEREMIAH P. HARRIMAN, a citizen of the United States, and a resident of Woonsocket, county of Providence, and 5 State of Rhode Island, have invented and produced a new and original Design for Surface Ornamentation of Knitted Fabrics, of which the following is a full, clear, and exact description, reference being had to the accompanying 10 photographic illustration, forming a part hereof, in which is represented a portion of a fabric with my design applied thereto.

My design is intended for application, generally, to all forms of knitted fabrics to which 15 it is desired to impart an ornamental appearance; and it consists of a series of parallel stripes which are disposed diagonally of the fabric with respect to the successive rows or courses of loops composing the same and made 20 up from a number of short stripes arranged at an angle to the former, all as will hereinafter more fully appear.

In the photographic illustration these stripes are shown at A A, &c., the same extending diagonally across the fabric at any desired angle 25 with respect thereto and at a distance apart about equal to the width of one of said stripes.

The stripes as thus described, instead of being made continuous and unbroken throughout their entire lengths, are composed of a number 30 of short stripes, a a, which are disposed at an angle to the general direction of the stripes A A, all as shown.

I am aware that it is not new to ornament knitted fabric with longitudinal and transverse stripes, and also that checks have been employed for the same purpose. These I do not claim; but,

Having fully described my design, what I do claim, and desire to secure by Letters Patent 40 of the United States, is—

The design for surface ornamentation of knit- 45 ted fabrics, consisting of a series of parallel stripes arranged diagonally of the fabric with respect to the successive rows or courses of loops composing the same, and made up from a number of short stripes disposed at an angle thereto, as shown and described.

In testimony whereof I have hereunto set my hand this 27th day of February, 1888.

JEREMIAH P. HARRIMAN.
